(57) **CLAIM**

The ornamental design for a support bracket, as shown and described.

DESCRIPTION

FIG. 1 is a front perspective of a support bracket according to a first embodiment of the present disclosure, the precise length of the support bracket is not claimed;

FIG. 2 is a front view of the support bracket of FIG. 1;

FIG. 3 is a top view thereof;

FIG. 4 is a rear view thereof;

FIG. 5 is a bottom view thereof;

FIG. 6 is a right side view thereof;

FIG. 7 is a left side view thereof;

FIG. 8 is a front perspective of a support bracket according to a second embodiment of the present disclosure, the precise length of the support bracket is not claimed;

FIG. 9 is a front view of the support bracket of FIG. 8;

FIG. 10 is a top view thereof;

FIG. 11 is a rear view thereof;

FIG. 12 is a bottom view thereof;

FIG. 13 is a right side view thereof;

FIG. 14 is a left side view thereof;

FIG. 15 is a front perspective of a support bracket according to a third embodiment of the present disclosure, the precise length of the support bracket is not claimed;

FIG. 16 is a front view of the support bracket of FIG. 15;

FIG. 17 is a top view thereof;

FIG. 18 is a rear view thereof;

FIG. 19 is a bottom view thereof;

FIG. 20 is a right side view thereof; and,

FIG. 21 is a left side view thereof.

The broken lines in the drawings depict portions of the support bracket that form no part of the claimed design.

The symbolic break lines (e.g., pairs of dash-dash broken lines) immediately adjacent the solid lines represent a boundary between claimed and unclaimed subject matter

(Continued)

and form no part of the claimed design. The appearance of any portion of the article between the break lines forms no part of the claimed design.

1 Claim, 18 Drawing Sheets
